GIOVANNI BOGGERO, OF TURIN, ITALY, ASSIGNOR TO S. A. B. I. E. SOCIETÀ ANONIMA
BREVETTI ITALIANI ESTERI, OF TURIN, ITALY

TELEGRAPHIC AND WIRELESS TRANSMISSION SYSTEM

Application filed September 12, 1929, Serial No. 392,167, and in Italy December 14, 1928.

This invention relates to telegraphic and wireless transmission systems, wherein groups of two or more variable frequencies are utilized for the formation of signal combinations said frequencies being produced by the depression of the keys of an ordinary typewriter keyboard and transmitted to the receiving station by any radiant energy such as Hertzian waves, carrier waves, electric currents and the like.

According to this invention each group of two or more variable frequencies representing a signal is obtained by means of an oscillating circuit comprising at least a thermionic tube, 15 a constant inductance and two or more capacities generating two or more frequencies, the combination of which represents the signal to be transmitted.

A characteristic feature of this invention 20 consists in the fact that the frequencies of each group are transmitted in succession at a very short interval from one another and for this purpose a distributor is provided which, when the key corresponding to the signal to 25 be transmitted is depressed, will lead in due sequence the different capacities corresponding to the signal to be transmitted to the oscillating circuit.

A damper arranged on the distributor and 30 a relay series will ensure the exact time connection and disconnection of said capacities.

To prevent any interference, it is necessary 35 that the frequencies of each group be absolutely constant during transmission. This may be obtained by maintaining the inductance value constant and as the inductance is influenced by the variation of the field of the inductance winding due to unavoidable variation of the plate current, according to 40 this invention, a secondary compensating inductance is wound on the main inductance through which the current flows in opposite direction, said compensating inductance being such as to automatically compensate the 45 variation of the main inductance. Owing to this arrangement, the frequencies of each group are maintained perfectly distinct from one another.

According to another constructional form 50 of this invention, the frequency variation

by the depression of the keys or they may be obtained using variable inductances in lieu of capacities. Said inductances may be connected in series and the combinations of frequencies representing the signals may be obtained by means of changers operated 55 be connected in series for predetermined frequency values and in parallel for the intermediate values. For said intermediate values capacities may also be used instead of inductances in parallel.

The receiving station comprises broadly a receiving apparatus which may be of any suitable type and a printing machine for printing the received message on a sheet of 60 paper.

The modulation waves energize a group of calling resonators adapted to bring the printing machine in a ready for typewriting condition and operate thereafter the printing 65 machine.

According to this invention the calling resonators which are energized when the transmitting station sends off a predetermined signal which individualizes the receiving station, with which it is desired to communicate, close a circuit which starts the motor of the printing machine and closes a switch which prepares the circuits of the receiving set so that they will be ready for the 70 reception.

The printing machine comprises a combinator, by means of which the circuits controlling a relay are closed in the due sequence, said relay operating a hammer acting on a 75 type wheel in such a way as to print the symbol corresponding to the received signal on a sheet of paper placed on a carrier, an electromagnetic coupling moving the carrier through a spacing, so that it will be ready to 80 receive and print a new signal, and a relay to return the energized combining relays into their initial position.

The combinator may be constituted by a disk carrying on its periphery insulated contacts, on which slide two insulated contacts carried by an insulating arm moving synchronously with the type wheels in such a way as to close the signalling circuits in the 85 desired order and sequence by means of con- 90

tacts electromagnetically operated by the resonators. The combinator could also be constituted by a rotating cylinder of conductive material coated with a sheet of insulating material having slots and holes distributed in the manner of a ladder in order to close the signalling circuits in the desired succession.

The printing machine comprises moreover 10 arrangements to move the sheet forward and return the carrier to its initial position to begin the writing of a fresh line. These devices are automatically operated by means of circuits which are closed by the carrier 15 during its travel.

The annexed drawing shows by way of example, some constructional forms of this invention.

Figs. 1 and 1A show diagrammatically the 20 connections and the apparatus of the transmitting system;

Fig. 2 is an elevation partially sectioned of the distributor;

Fig. 3 shows diagrammatically the variable 25 inductances in series, which may be substituted to the capacities of Fig. 1;

Fig. 4 is a diagram of the variable inductances in series and in parallel, and

Fig. 5 shows a variable inductance to be 30 used in combination with the capacities.

Figs. 6 and 6A show diagrammatically the connections and apparatus of the receiving system;

Fig. 7 is a cross section of the resonator 35 group, and

Fig. 8 is a detail of the printing carrier.

Referring to Figs. 1 and 2, 1 denotes a thermionic tube, wherein a filament 2 is fed by a battery 3 by means of a circuit 4 comprising 40 an adjustable ohmic resistance 5, a plate 6 being connected in series with a compensating inductance 7.

8 is the battery of the plate circuit; 9a, 9b, 45 9c, 9d . . . denote condensers adapted to generate successive pairs of frequencies constituting the signals and successively connected two by two in the oscillating circuit, as it will be more clearly set forth hereafter. 10 is a main inductance wound on the same 50 core 11 of the secondary compensating inductance 7 and connected between the grid circuit 12 and the positive pole of the battery 8. An ohmic resistance 13 is provided for controlling the value of the main inductance 55 to the desired degree, said ohmic resistance 13 being connected at one end with the negative pole of the battery 3 and provided at its other end with a movable contact by means of which it is possible to control the number 60 of turns of the inductance connected to the resistance circuit.

The condensers 9a, 9b, 9c, 9d . . . are connected two by two and according to a predetermined sequence to the oscillating circuit 65 by means of relays 14a, 14b, 14c, 14d respec-

tively, which are energized by means of keys 15a, 15b . . . corresponding to the signals to be transmitted by means of the distributor 16.

Said distributor (see particularly Fig. 2) 70 comprises a bell-shaped electromagnet 17 secured inside a case 18 carrying axially a shaft 19 rotatably mounted in suitable supports and provided at its upper part with a steep-pitched thread 20, engaging a hub connected with an armature 21, which is prevented from rotating by notches in which guiding rods 22 secured to the electromagnet are engaged. By this arrangement, when the electromagnet is energized, its armature is attracted and causes the shaft 19 to accomplish a turn in one direction, and when it is de-energized, a spring (not shown in the drawing for the sake of simplicity) returns the armature into its position of rest, causing the shaft to turn in the opposed direction. 75

The shaft 19 passes through a cover 23 of insulating material and carries on its protruding portion a resilient arm 24 on the free end of which is secured by means of 80 screws 25 an electrically insulated spider of conductive material. The cross arms 26a and 26b of the spider carry at their ends contacts which cooperate with a sector of conductive material 27 and a pair of contacts 28a 28b (electrically insulated from the distributor body) respectively. In the position of rest (shown in Fig. 1) the contacts 26a and 26b are held raised from the 85 cooperating contacts by the resilient arm. For carrying said contacts into their operating position or in other words to depress them when they are caused to rotate by the shaft 19, an arm 29 is provided which carries at its free end a cam 30 cooperating with 90 the bevelled ends 31 of a guiding sector 32, in order to force the contacts 26a and 26b against the sector 27 and series of contacts 28a, 28b respectively when the armature 21 is attracted by the electromagnet and to raise them when the armature is returned into its position of rest. For this purpose the cam and bevelled ends are shaped in such 95 a way as to force the end of the arm 29 to slide on the lower surface of the guiding sector 32 during operation and to pass on the upper surface of said sector during their return stroke. 100

The energizing coil of the electromagnet 17 is connected with a feeding battery 33 by means of a circuit 34 including a switch comprising a fixed contact adjustable by means of a screw 35 and a spring contact 36 actuated by a lever 37, as it will be more clearly described hereafter. 110

The sector 27 is connected to the positive pole of the battery 33 by means of a conductor 38, while the two contacts 28a, 28b are connected by means of conductors 39a, 39b respectively to a series of elastic contact 115

pieces 40a, 40'a . . . and 40b, 40'b . . . having the form of an inverted V. The contact pieces 40a, 40'a . . . cooperate with fixed contacts 41a, 41'a . . . electrically connected to one another and by means of a conductor 42a to one end of the energizing winding of the relay 14a.

The contact pieces 40b, 40'b cooperate with fixed contacts 41b, 41c insulated from one another and connected by means of conductors 42b, 42c, 42d to the energizing winding of the relays 14b, 14c, 14d . . . respectively. The other ends of the energizing windings of the relays 14a; 14b; 14c; 14d . . . are connected by means of a common conductor 43 to the negative pole of the battery 33.

When a key, for instance the key 15a, is depressed the contacts 40a, 40b are simultaneously forced towards the fixed contacts 41a, 41b; the circuits for the coils of the relays 14a, 14b are thus prepared. By continuing the pressure on the key, a tooth 44, secured to its stem, strikes a lever 37 thus bringing the spring contact 36 in engagement with the contact 35. Thereby the energizing circuit 34 of the electromagnet 17 is closed; said electromagnet on being energized, attracts its own armature 21 and causes the shaft 19 and therefore the spider to rotate; the contacts 26a and 26b of this latter are depressed owing to the engagement of the cam 30 on the lower surface of the guide 32. The windings of the relays 14a, 14b are thus successively brought into the circuit on the battery 33 and said windings, when energized, successively close the circuits on the condensers 9a, 9b, which successively translate the two frequencies representing the signal, to a carrier wave transmitting circuit through the transformer 45.

A damper in an oil bath (see Fig. 2) is provided in order to ensure a perfectly uniform rotating movement of the spider and the closure of the circuits at regular intervals. Said damper consists of a small blade wheel 46 rotatably mounted in a container 47 filled with oil, coaxially mounted on the distributor bottom; the shaft 48 of the blade wheel extends into the case 18 of the distributor and is connected with the shaft 19 arranged on the same axis by means of a helicoidal spring 49.

A locking device comprising a shaft 50 having a slot 51 traversed by the tooth 44 is arranged in order to prevent the opening of the energizing circuit of the distributor electromagnet before the spider has accomplished its stroke. When the tooth 44 has moved under the shaft and has closed the energizing circuit of the electromagnet of the distributor, the shaft 50 is caused to rotate so that its solid portion will be brought on the path of the tooth 44. This rotation is effected by means of a relay 52 connected in

parallel to the circuit 34 and the armature 53 of which actuates by means of a rod 54 an arm 55 keyed on the shaft 50. When the spider has accomplished its operating stroke and has been returned into its position of rest the circuit 34 is opened and the armature 53 is returned into its position of rest by the spring 56.

The formation of the groups of frequencies constituting the symbols to be transmitted may be effected by placing variable inductances in the circuit of the main inductance 10, instead of using the capacities 9a; 9b; 9c; 9d.

Fig. 3 shows diagrammatically a group of variable inductances 57a, 57b, 57c, 57d . . . which may be advantageously used in the place of the capacities 9a, 9b, 9c, 9d . . . Each one of said inductances is subdivided in sections abutting stationary contacts 58, 85 on which slides a contact carried by a rotating arm 59. In the illustrated example each inductance is subdivided into ten sections and each rotating arm 59 carries an index 60 sliding along a scale 61 carrying the corresponding number.

It will be easily understood that by the above arrangement a nearly unlimited number of combinations of groups of two frequencies representing the signals to be transmitted will be obtained. Said groups are translated to the transmitting circuit by means of the distributor already described with reference to Figs. 1 and 2.

Fig. 4 shows a more compact arrangement, wherein an inductance 62 is connected in series to the main inductance. Auxiliary inductances 63 are branched at predetermined points on the inductance 62 provided with changers 64 similar to those described with reference to Fig. 3. By means of said changers it will be possible to obtain all the intermediate frequencies between the frequencies corresponding to the taps 65 of the inductance 62.

Fig. 5 shows a modified form, wherein a variable inductance 65 may be combined with capacities, as shown in Fig. 1. In this case the capacities will be utilized to obtain the intermediate frequencies between the value 115 of the frequencies corresponding to the taps of the inductance 65.

It will of course be seen that other combinations of inductances and capacities may be used for representing the symbols to be transmitted and also other mechanical or electrical arrangements may be used to obtain the same timed variations and transmissions of frequencies without departing from the spirit of this invention.

Referring to Fig. 6, the receiving station comprises a group of resonators 100 having as many resonating elements as there are vario-generators of frequency (9 in the illustrated example), a group of recombining 120

relays 101¹ to 101⁹, each relay being energized by means of a circuit, the closure of which is controlled by the corresponding resonating element, a set of contacts 102¹ to 102⁹ carried 5 by an insulating bar, a recombinator 103 carrying a circular set of equidistant contacts 104 formed by four groups of nine contacts numbered I to IX and suitably distributed in such a way as to obtain a continuous 10 succession of contact pairs representing the signals to be transmitted (36 in the illustrated example corresponding to the keyboard keys of the transmitting group). The contacts bearing the same number are connected to each other and to the corresponding contacts 102 cooperating with the recombinating relays 101. A rotating arm carrying two contact pieces 105 and 106 slides on the contacts of the recombinator; said contact pieces 105 and 106 are electrically separated by a distance equal 20 to the distance between the contact 104; one of said contacts is connected to ground at 107 and the other is connected to a pair of polarized relays 108 operating a main switch 109 controlling a circuit actuating a printing carrier and an electromagnetic coupling for printing the received signal and then moving the carrier forward. The receiving station 25 is called by means of a conventional calling signal, which in the illustrated example is represented by two frequencies, to which the elements 100¹ and 100⁹ of the resonator will respond. When the transmitting station 30 sends off the frequency corresponding to the element 100¹, this latter is set into vibration and only when it reaches the full width of movement, thereby closing a circuit extending from ground at 111, resistance 112, conductor 113, relay winding 101¹ and conductor 114, to the negative pole of the battery. The relay 101¹ when energized forces its armature into engagement with the contact 100¹ and thus the calling circuit is prepared. 35 The frequency arriving being in resonance with the element 100⁹ this latter, as above described, will close the energizing circuit for the relay 101⁹; which, on being energized, forces its own armature into engagement 40 with the contact 102⁹ thus completing the calling circuit, which includes an auxiliary calling battery 115 and extends from the positive pole of said battery through the conductor 116, contact 102¹, armature of the relay 101¹, conductor 117, armature of the relay 101⁹, contact 102⁹, conductor 118 to the winding of the calling relay 119 and conductor 120 to the negative pole of the battery 115. 45 The relay 119 when energized attracts its own armature 121, thus closing a circuit extending from earth at 122, through the motor 123, conductor 124, core of the relay 119; armature 121 and conductors 125 and 114' to 50 the negative pole of the battery 110.

The motor 123 is started and gives a rotary movement to the arm 105—106 of the recombinator, type wheel and loose member of the electromagnetic coupling. In order to keep the motor going even when the energizing circuit above described is open, the calling relay 119 is provided with a coil 126 which maintains the armature 121 in the attracted position. Said coil is connected in parallel with the motor on the energizing circuit above described. 70

The rotating arm 105—106, when reaching the adjacent contacts I—IX of the disk of the recombinator 103, closes a recombinatory circuit extending from the ground contact 106 through a contact 104¹, conductor 127, contact 102¹, armature of the relay 101¹, conductor 117, armature of the relay 101⁹, contact 102⁹, conductor 128, contacts 104^{IX} and 105, conductor 129, polarized relays 108, conductors 130 and 131, armature 132 and conductors 133 to the negative pole of the battery 110. On closure of the recombinatory circuit the polarized relays 108 are energized, and carry the spring contact 109 on the right against the core of the relay on the right side. A printing circuit is thereby closed extending from the negative pole of battery 110, through the conductor 133, armature 132, conductor 131, spring contact 109, core of the right relay 108, conductor 134 and coil of the printing relay 135 to ground at 136. The relay 135 when energized actuates a hammer which strikes the symbol of the type wheel 142 represented by the two frequencies acting on the resonators 100¹ and 100⁹ said symbol having been brought under the hammer synchronously with the arm 105 or 106. 90

At the same time a circuit is closed in parallel with the circuit above described which energizes, through the conductor 127, the exciting coil of the electromagnetic coupling 138, which will thus be closed setting the threaded shaft 139 in rotation, which moves the printing carrier 140 forward, a ratchet wheel 141 being keyed on said shaft. 105

Finally a third circuit is closed through a relay 149 resetting the armatures of the recombinatory relays 100¹ . . . 100⁹; said resetting relay, attracting its own armature 150 closes a circuit extending from ground at 151, through the armature 150, conductor 152, resetting coils 153 of the actuated recombinatory relays 100¹ and 100⁹, conductors 154 and 114' to the negative pole of the battery 110. The armatures of the relays 101¹ and 101⁹ are separated from the cooperating contacts 102 whereby the above described recombinatory circuit is opened. 115

The rotation of the ratchet wheel 141 raises the pawl 142 which passing from one tooth to another closes for the time being through the contact 143 a circuit extending from the negative pole of the battery 110 through the conductor 144, primary 125

130

winding 145 of a transformer, conductor 146 and contact 143 to ground at 147. As soon as this circuit is opened, an electromotive force is generated in the secondary winding 148, said electromotive force energizes the polarized relay 108 on the left and disengages the one on the right carrying the spring contact 109 on the left into the position of rest.

- 10 The printing circuit is thus interrupted, the coupling is disengaged and disengaged thus stopping the forward movement of the carrier, the resetting relay 149 is disengaged and disengaging its armature 150
- 15 opens the resetting circuit. The motor continues its rotation causing the arm 105—106 of the recombinator and the loose member of the electromagnetic coupling to turn, the receiving and printing apparatus is therefore
- 20 ready to receive the message and each time a pair of frequencies is received the above described operations will occur.

When the carrier reaches the end of its stroke, that is when the writing of a line is completed it strikes a contact 155, closing a circuit extending from ground 136, through the contact 155, conductor 156, winding of a relay 157 locking the carrier, conductor 158, spring contact 159, conductors 160 and 114 to the negative pole of the battery 110. The relay 157 when energized attracts the arm 161 of the pawl 142, disengaging the ratchet wheel, so that the carrier is forced by the spring towards the left and causes the steep-pitched screw 139 to turn in a direction opposed to the forward direction. In order to maintain the pawl 142 raised during the movement of the carrier, the pawl is connected to ground and the core of the stop relay 157 is connected by means of the conductor 162 to the conductor 156, that is to one end of the energizing winding of said relay; the above described circuit remains thus closed even when the carrier is separated from the contact 155.

Simultaneously with the energizing of the relay 157 the relay 163 is energized which attracting the armature 132 breaks the recombinatory circuit in order to prevent an accidental formation of the following combination during the return of the carrier. Moreover the relay 164 is energized for the forward movement of the paper and, by means of a lever 165 connected to its armature and a ratchet and pawl mechanism 166, causes the shaft 167 of the paper roller 168 to perform a rotation through a spacing. The relays 163 and 164 are connected in parallel to the relay 157, so that, when the carrier reaches the end of its stroke towards the left and meets the spring contact 159 it breaks the circuit of all said relays, which, on becoming disengaged set their armature free, said armatures returning into their initial position as shown in the drawing.

At the end of the message writing the motor 123 must be stopped in order to avoid a free run thereof. For this purpose a relay may be arranged to break the energizing circuit of the motor, said relay may be actuated by the transmitting station automatically a certain time after the transmission is over. Means can also be provided to displace the paper through a distance corresponding to two or more spacings when the writing of the telegram is ended, in such a way as to separate a telegram from the following one.

What I claim is:

1. In a signalling system, the combination with a transmitting station, a receiving station, an oscillating circuit at the transmitting station comprising a plurality of capacities which can be successively connected to said oscillating circuit, a keyboard at the transmitting station to close said oscillating circuit and a printing apparatus at the receiving station, of means at the transmitting station to close in succession at each depression of a key the oscillating circuit through two of said capacities in order to superpose on a carrier wave of constant frequency two successive waves of different frequencies representing the symbol of the depressed key, resonating means at the receiving station tuned to said frequencies and means operated by the resonating means for preparing circuits operating the printing apparatus on the arrival of the first frequency and to complete said circuits on the arrival of the second frequency.

2. In a signalling system, the combination with a transmitting station, a receiving station, an oscillating circuit at the transmitting station comprising a plurality of capacities adapted to be successively connected to said oscillating circuit, a main inductance and a compensating inductance, a keyboard at the transmitting station to close said oscillating circuit and a printing apparatus at the receiving station, of a distributor at the transmitting station to close, in succession at each depression of a key, the oscillating circuit through two predetermined capacities in such a way as to superpose on a carrier wave of constant frequency two successive waves of different frequencies representing the symbol of the depressed key, resonators at the receiving station tuned to said frequencies and means operated by the resonators for preparing actuating circuits of the printing apparatus on arrival of the first frequency and to complete said circuits on arrival of the second frequency.

3. In a signalling system, the combination with a transmitting station, a receiving station, an oscillating circuit at the transmitting station comprising a plurality of capacities adapted to be successively connected to said oscillating circuit, a keyboard at the trans-

mitting station to close said oscillating circuit and a printing apparatus at the receiving station, of a distributor at the transmitting station comprising a bell-shaped electromagnet energized by the depression of any key, an armature, a shaft having a steep-pitched thread on which said armature is fitted, means to prevent said armature from rotating, a spider having movable contact pieces carried by an elastic arm keyed on said shaft, stationary contact pieces, means to bring said movable contact pieces in engagement with said stationary contacts during the operative stroke when said electromagnet is energized and to disengage said movable contact pieces from the stationary contacts during the return stroke when said electromagnet is deenergized, of a plurality of relays, each one of said relays being adapted to close the oscillating circuit on one of said capacities, said relays being included in a circuit comprising a source of energy, said distributor and a set of switches actuated two by two each key of the keyboard in such a way as to connect to said circuit in succession two of said relays each time a key is depressed to close in succession the oscillating circuit on two corresponding capacities, thus superposing on a carrier wave of constant frequency two successive waves of different frequencies, resonators at the receiving station tuned to the frequencies of the oscillating circuit and means actuated by the resonators for preparing the circuits operating the printing apparatus on arrival of the first frequency and completing said circuits on arrival of the second frequency.

4. In a signalling station, as claimed in claim 3, a blade damper for the distributor connected by elastic means to the shaft having a steep-pitched thread.

5. In a signalling system, the combination with a transmitting station, a receiving station, an oscillating circuit at the transmitting station comprising a plurality of capacities adapted to be connected in succession to said oscillating circuit, a keyboard at the transmitting station to close said oscillating circuit and a printing apparatus at the receiving station, of a plurality of relays corresponding in number to said capacities for including in succession said capacities in said oscillating circuit, an energizing circuit for said relays comprising switches actuated two by two by the keys and a distributor to close in succession said energizing circuit on two of said relays corresponding to the symbol of the depressed key, in such a way as to transmit two waves of different frequencies on a carrier wave of constant frequency, an operating electromagnet for said distributor, a circuit for said electromagnet, a switch in said circuit, a tooth carried by each key to close said circuit when said key is depressed, a device for locking said key in the depressed position until completion of

the distributor operation, resonators at the receiving station tuned to said frequencies and means operated by said resonators for preparing actuating circuits of the printing apparatus on arrival of the first frequency and completing said circuits on arrival of the second frequency.

6. In a signalling system, as claimed in claim 5, a key locking device comprising a latch and a relay acting on said latch and included in the energizing circuit of the electromagnet of the distributor.

7. In a signalling system, the combination with a transmitting station, a receiving station, an oscillating circuit at the transmitting station comprising a plurality of capacities adapted to be connected in succession to said oscillating circuit, a keyboard at the transmitting station to close said oscillating circuit and a printing apparatus at the receiving station, of means at the transmitting station to close in succession on each depression of a key the oscillating circuit through two of said capacities in such a way as to superpose on a carrier wave of constant frequency two successive waves of different frequencies representing the symbol of the depressed key, a group of resonators at the receiving station having a number of resonating elements equal to the number of said capacities, a group of combinatory relays, an energizing circuit for said relays, the closure of which is controlled by the resonating element brought to oscillate on arrival of the corresponding frequency and a recombinator closing the circuits controlling the printing apparatus.

8. In a signalling system the combination with a transmitting station, a receiving station, an oscillating circuit at the transmitting station comprising a plurality of capacities adapted to be connected in succession to said oscillating circuit, a keyboard at the transmitting station to close said oscillating circuit and a printing apparatus at the receiving station, of means at the transmitting station to close in succession, on each depression of a key the oscillating circuit through two of said capacities in such a way as to superpose on a carrier wave of constant frequency two successive waves of different frequencies representing the symbol of the depressed key, a group of resonators at the receiving station having a number of resonating elements equal to the number of said capacities, a group of combinatory relays, an energizing circuit for said relays, the closure of which is controlled by the resonating element brought to oscillate on arrival of the corresponding frequency, a recombinator constituted by a disk carrying a circular set of fixed contacts numbered according to a predetermined order to form the combinations constituting the symbols, the contacts bearing the same numbers being electrically

connected to each other and to the contact of the corresponding recombinatory relay, a rotating arm carrying two insulated contacts cooperating with said set of fixed contacts, 5 a source of energy, one pole of which is connected to one of said movable contacts, a pair of polarized relays connected in series to the other pole of said source of energy and to the other movable contact, a control 10 circuit for the printing apparatus and a switch included in said control circuit and controlled by said polarized relays.

9. In a signalling system, in combination, a transmitting station comprising an oscillating circuit having a number of capacities adapted to be connected successively to said oscillating circuit, a keyboard, to close said oscillating circuit and means to close in succession, on each depression of a key the oscillating circuit through two of said capacities in order to superpose on a carrier wave of constant frequency two successive waves of different frequencies representing the symbol of the depressed key, a receiving station 25 comprising a source of energy, a motor, a printing apparatus constituted by a stepwise advancing carrier, a type wheel fitted in said carrier and receiving a uniform movement from said motor, an electromagnetic coupling 30 through which the stepwise forward movement of the printing carrier is effected, a printing electromagnet, an energizing circuit for said electromagnet, a recombinator comprising a circular series of fixed contacts 35 and an arm having two insulated contacts and receiving from said motor a rotating movement in synchronism with the type wheel motion, said recombinator being placed in the control circuit of the printing apparatus, 40 a group of resonators having a number of resonating elements equal to the number of capacities, a group of recombinatory relays, an energizing circuit for said relays, the closure of which is controlled by the resonating elements thrown into operation, on arrival of the corresponding frequencies, said relays controlling the motor circuit and preparing the controlling circuit of the printing electromagnet and electromagnetic coupling, 45 said circuit being completed when the recombinator arm slides on the fixed contacts corresponding to the received symbol.

50 10. In a signalling system, in combination, a transmitting station comprising an oscillating circuit having a number of capacities adapted to be successively connected to said oscillating circuit, a keyboard and means for closing successively, each time a key is depressed, the oscillating circuit through two of said capacities in such a way as to superpose on a carrier wave of constant frequency two successive waves of different frequencies representing the symbol of the depressed key, 55 a receiving station comprising a source of

energy, a motor, a stepwise advancing carrier carrying a type wheel receiving a uniform motion from said motor, an electromagnetic coupling, through which the stepwise forward movement of said carrier is effected, a printing electromagnet, an energizing circuit for said electromagnet, a recombinator comprising a circular set of fixed contacts and an arm having two insulated contacts and receiving from said motor a rotary movement in synchronism with the type wheel motion, 60 said recombinator being included in the controlling circuit of the printing apparatus, a group of resonators having a number of resonating elements equal to the number of capacities, a group of recombinatory relays, the energizing circuit of which is controlled by said resonating elements which are thrown into operation on arrival of the corresponding frequencies, said relays 65 controlling the energizing circuit of said motor and preparing the energizing circuit of the printing electromagnet, said circuit being completed when the recombinator arm slides on the fixed contacts corresponding to the received symbol; a main switch included in the energizing circuit of the printing electromagnet and electromagnetic coupling, a pair of polarized relays controlling said switch, a circuit comprising said relays and a transformer and a switch operated by means of a pawl and ratchet device to generate in said transformer a current capable of actuating said polarized relays in such a way as to open said main switch when the printing of the received symbol has been completed.

70 11. In a signalling system, in combination, a transmitting station comprising an oscillating circuit having a number of capacities adapted to be successively connected to said oscillating circuit, a keyboard and means for closing successively, each time a key is depressed, the oscillating circuit through two of said capacities in such a way as to superpose on a carrier wave of constant frequency two successive waves of different frequencies representing the symbol of the depressed key, a receiving station comprising a source of energy, a motor, a stepwise advancing carrier carrying a type wheel receiving a uniform motion from said motor, an electromagnetic coupling, through which the stepwise forward movement of said carrier is effected, a printing electromagnet, an energizing circuit for said electromagnet, a recombinator comprising a circular set of fixed contacts and an arm having two insulated contacts and receiving from said motor a rotary movement in synchronism with the type wheel motion, 75 said recombinator being included in the controlling circuit of the printing apparatus, a group of resonators having a number of resonating elements equal to the number of capacities, a group of recombinatory relays, the energizing circuit of which is con-

trolled by said resonating elements which are thrown into operation on arrival of the corresponding frequencies, said relays controlling the energizing circuit of said motor and preparing the energizing circuit of the printing electromagnet, said circuit being completed when the recombinator arm slides on the fixed contacts corresponding to the received symbol, a main switch included in the energizing circuit of the printing electromagnet and electromagnetic coupling, a pair of polarized relays controlling said switch, a circuit comprising said relays and a transformer and a switch operated by means of a pawl and ratchet device to generate in said transformer a current capable of actuating said polarized relays in such a way as to open said main switch when the printing of the received symbol has been completed and means for breaking the energizing circuits of the printing electromagnet and electromagnetic coupling when the carrier is at the end of its stroke.

12. In a signalling system, in combination, a transmitting station comprising an oscillating circuit having a number of capacities adapted to be successively connected to said oscillating circuit, a keyboard and means for closing successively, each time a key is depressed, the oscillating circuit through two of said capacities in such a way as to superpose on a carrier wave of constant frequency two successive waves of different frequencies representing the symbol of the depressed key, a receiving station comprising a source of energy, a motor, a stepwise advancing carrier carrying a type wheel receiving a uniform motion from said motor, an electromagnetic coupling, through which the stepwise forward movement of said carrier is effected, a printing electromagnet, an energizing circuit for said electromagnet, a recombinator comprising a circular set of fixed contacts and an arm having two insulated contacts and receiving from said motor a rotary movement in synchronism with the type wheel motion, said combinator being included in the controlling circuit of the printing apparatus, a group of resonators having a number of resonating elements equal to the number of said capacities, a group of recombinatory relays, the energizing circuit of which is controlled by said resonating elements which are thrown into operation on arrival of the corresponding frequencies, said relays controlling the energizing circuit of said motor and preparing the energizing circuit of the printing electromagnet, said circuit being completed when the recombinator arm slides on the fixed contacts corresponding to the received symbol, a main switch included in the energizing circuit of the printing electromagnet and electromagnetic coupling, a pair of polarized relays controlling said switch, a circuit comprising said relays, a transformer

and a switch operated by means of a pawl and ratchet device to generate in said transformer a current capable of actuating said polarized relays in such a way as to open said main switch when the printing of the received symbol has been completed, and means for breaking the energizing circuits of the printing electromagnet and electromagnetic coupling when the carrier is at the end of its stroke, means for the forward movement of the paper on which the printing is effected, and means for breaking the recombinatory circuit for the purpose of preventing that during the movement of the carrier the printing device be influenced by the arrival of a successive signal.

In testimony that I claim the foregoing as my invention, I have signed my name.

GIOVANNI BOGGERO.
